UNITED STATES PATENT OFFICE.

JOHN E. FOLEY, OF PONTIAC, MICHIGAN.

VEHICLE-WHEEL.

No. 850,636.

Specification of Letters Patent.

Patented April 16, 1907.

Application filed January 25, 1907. Serial No. 354,003.

To all whom it may concern:

Be it known that I, JOHN E. FOLEY, a citizen of the United States, residing at Pontiac, county of Oakland, State of Michigan, have 5 invented a certain new and useful Improvement in Vehicle-Wheels; and I declare the following to be a full, clear, and exact description of the same, such as will enable others skilled in the art to which it pertains to 10 make and use the same, reference being had to the accompanying drawings, which form a part of this specification.

My invention relates to an improvement in vehicle-wheels shown in the accompanying 15 drawings and more particularly set forth in the following specification and claims.

In the drawings, Figure 1 is a longitudinal sectional view through a wooden vehicle-hub provided with encircling sheet-metal bands. 20 Fig. 2 is a perspective view of one portion of the inner band encircling the hub and through which the spokes project. Fig. 3 is an elevation of the two parts composing the inner band, showing the parts assembled. Fig. 4 25 is an end view of the hub with parts broken away to show the location of the bolts in the spokes, whereby the spokes are secured without being weakened, while the bolts engage the outside bands. Fig. 5 is a longitudinal 30 section of a detail of the hub, showing a variation in the form of the outside bands at the point where they overlap the inner band. Fig. 6 is a similar longitudinal section of a detail of the bands of the hub, showing another variation at the point where the bands 35 overlap.

The object of this invention is to provide an inner band capable of inclosing that portion of the hub from which the spokes project, the construction being such that the parts constituting the inner band may be assembled over the hub, after which the outer bands are forced on from either end, thus 40 completely inclosing the wooden hub and at 45 the same time securing the inner band against displacement.

I have shown in the drawings several modifications in the form of the outer bands at the point where these parts overlap the inner band, the object being to present a finished appearance and to overlap the parts in such manner as to guard against the entry of moisture.

Referring to the letters of reference shown 50 in the drawings, A is a wooden hub of a vehicle-wheel, and B are its spokes.

C and C' are sleeves or encircling bands of sheet metal, each having an upturned flange c, the edge of the upturned flange being bent inwardly, as indicated at c'. 60

D is an inner annular channel-band formed in two parts and provided with apertures d for the passage of the spokes, being embraced between the upstanding flanges c of the outside bands C and C'. 65

E are bolts engaging the inner and outer bands. As shown in Fig. 4, the bolts E project through apertures in the spokes at a point where the opening will not weaken the 70 spoke, the bolts serving also to secure the spokes to the hub.

F are wooden dowel-pins alternating with the bolts E for fastening the spokes to the hub. While a sufficient number of bolts E 75 may be employed to engage all of the spokes, it is not necessary to use this number to bind the outer bands together, hence the employment of the dowel-pins alternately with the bolts.

Having thus described my invention, what I claim is— 80

1. In a vehicle-wheel, a hub, an encircling band formed in two parts provided with apertures through which the spokes project, outside bands with upstanding flanges located on either side of the first-named band, and means for connecting the upstanding flanges of the outside bands with the first-named band, substantially as described. 85

2. In a vehicle-wheel, an encircling band 90 channel-shaped and formed in two parts, said band provided with apertures through which the spokes project, in combination with outer bands sleeved on the hub, said outer bands provided with upstanding flanges 95 adapted to overlap the walls of the channel-shaped flange, and bolts for securing the bands together and upon the hub, substantially as described.

3. In a vehicle-wheel, a hub, bands sleeved 100 upon the hub from either end provided with upstanding flanges, a channel-shaped band housed within the upstanding flanges, said channel-shaped band provided with openings through which the spokes of the wheel 105 project, and bolts securing the outer and inner bands and spokes to the hub, substantially as described.

4. In a vehicle-wheel, a hub, a channel-shaped band formed in two parts and provided with openings through which the 110 spokes project, encircling bands adapted to

be sleeved upon the hub from either end provided with upstanding flanges, said flanges having an inwardly-bent annular rim to project over and embrace the channel-shaped band when assembled, and bolts for securing the bands together upon the hub, substantially as described.

5. In a vehicle-wheel, a hub, bands sleeved upon the hub from either end provided with upstanding flanges, a channel-shaped band housed within the upstanding flanges, said

channel-shaped band provided with openings through which the spokes of the wheel project, bolts engaging the outer and inner bands, and dowel-pins to secure the spokes to the hub, substantially as described. 15

In testimony whereof I sign this specification in the presence of two witnesses.

JOHN E. FOLEY.
